(57) **CLAIM**

The ornamental design for a cable splitter, as shown and described.

DESCRIPTION

FIG. 1 is a front perspective view of a cable splitter, showing our design;

FIG. 2 is a rear perspective view thereof;

FIG. 3 is rear view thereof;

FIG. 4 is a front view thereof;

FIG. 5 is a side view thereof;

FIG. 6 is an opposing side view thereof;

FIG. 7 is a top view thereof; and,

FIG. 8 is a bottom view thereof.

The broken lines showing the environment are for illustrative purposes only and form no part of the claimed design.
